(57) **CLAIM**

The ornamental design for a wheel and rim guarding mask, as shown and described.

DESCRIPTION

FIG. 1 is a perspective view of a wheel and rim guarding mask showing our new design;

FIG. 2 is a top plan view of the mask of FIG. 1;

FIG. 3 is a bottom plan view of the mask of FIG. 1;

FIG. 4 is a side elevational view of the mask of FIG. 1;

FIG. 5 is a perspective view of a second embodiment of a wheel and rim guarding mask showing our new design;

FIG. 6 is a top plan view of the mask of FIG. 5;

FIG. 7 is a bottom plan view of the mask of FIG. 5; and,

FIG. 8 is a side elevational view of the mask of FIG. 5.
